UNITED STATES PATENT OFFICE.

JOHN F. CAVANAGH, OF MERIDEN, CONNECTICUT, ASSIGNOR TO THE CONNECTICUT TELEPHONE & ELECTRIC CO., INC., OF MERIDEN, CONNECTICUT, A CORPORATION OF CONNECTICUT.

SPARK-COIL.

1,303,162.

Specification of Letters Patent.

Patented May 6, 1919.

Application filed August 15, 1918. Serial No. 250,017.

To all whom it may concern:

Be it known that I, JOHN F. CAVANAGH, a citizen of the United States of America, residing at Meriden, Connecticut, have invented 5 a new and useful Spark-Coil, of which the following is a specification.

The subject of this invention is a spark coil for ignition purposes and the objects which I have had in mind have been to gain 10 increased electrical efficiency, to improve the magnetic circuit of the coil structure and to simplify the construction of the coil.

In accordance with my invention the primary winding is placed outside the secondary winding and a magnetic shell for the return magnetic circuit is provided immediately surrounding the secondary winding, the condenser being located outside this magnetic shell and the whole being incased in a 20 suitable protective casing. This outer casing may also be made of magnetic material to form a parallel return path for the magnetic circuit.

The details of construction and other features of the invention will become apparent as the specification proceeds.

In the drawing I have illustrated my invention embodied in two of its practical forms, this with the understanding however 30 that the invention is susceptible of various modifications without departure from the true spirit and scope thereof.

In this drawing:

Fig. 1, is a longitudinal sectional view 35 of a coil embodying the features of the invention and constructed with an outer casing of magnetic material.

Fig. 2, is a cross sectional view of the same taken substantially on the plane of the line 40 2—2 of Fig. 1.

Fig. 3, is a vertical sectional view similar to Fig. 1, of a second form of invention having an outer casing of insulating or non-magnetic material.

The core of the coil which may be made 45 up of iron wire, as customary, is designated 5, the secondary winding is designated 6, and the primary winding 7.

The secondary winding is applied directly 50 to the core and the primary winding is applied on the outside of the secondary, the two windings being separated from each other and the secondary being separated 55 from the core by suitable insulating material.

Immediately around the primary winding is a magnetic element in the nature of a shell 8 which may be for instance of soft "Norway" iron. This magnetic element provides a return path for the magnetic circuit 60 and being located immediately adjacent the primary is very effective. The secondary in this construction being located adjacent the core is subjected to the strongest portion of the magnetic field. 65

Outside the magnetic shell is a condenser 9, the same being shown as made up in coil form entirely surrounding the magnetic shell. This places the condenser at a point relatively far removed from the influence of 70 the secondary winding and at the outer coolest portion of the structure. The capacity therefore will remain substantially constant, inasmuch as the temperature will not vary to a large extent at this outside point. 75

The condenser is preferably protected by a suitable casing, the same being shown in the first form as an outer magnetic shell 10. This outer shell forms a part of the magnetic return circuit, acting in parallel with the 80 inner magnetic element.

The ends of the coil structure are protected by end caps 11 and 12 preferably of insulating material which may be held together clamped in engagement with the 85 outer casing by means of a through bolt 13 and securing nuts 14 and 15.

The second form of the invention illustrated, is similar in general respects to the first form, the main distinction being that 90 the outer casing 16 instead of being of magnetic material, is of non-magnetic material, such as a suitable insulating compound. In this case the magnetic shell 8 constitutes the only magnetic return and it is for this reason 95 made somewhat heavier or of greater mass than the magnetic shell in the first form, as illustrated.

Suitable terminals for the primary and secondary circuits are provided, which may 100 be mounted on the insulating end caps as illustrated at 17, 18 and 19.

The advantages of the invention will be apparent to those skilled in this art, it being seen that the secondary and primary are so 105 disposed with respect to the magnetic core and the surrounding magnetic shell as to obtain the greatest efficiency from both and the condenser is so located as to be practically unaffected by the secondary and to be 110

maintained at as near a uniform temperature as possible and therefore of practically a constant capacity. The coil of this construction also is easily assembled and can be made quite compact in form.

I claim:—

1. In a spark coil, the combination of a magnetic core, a secondary on said core, a primary about said secondary, a magnetic element about said primary and a condenser outside said magnetic shell.
2. In a spark coil, the combination of a magnetic core, a secondary on said core, a primary about said secondary, a magnetic element surrounding and in close relation to said primary and a condenser outside and surrounding said magnetic shell.
3. In a spark coil, the combination of a magnetic core, a secondary on said core, a primary surrounding said secondary, a magnetic element immediately surrounding said primary, a condenser outside said magnetic shell and an outer casing inclosing the entire structure.
4. In a spark coil, the combination of a magnetic core, a secondary on said core, a primary surrounding said secondary, a magnetic element immediately surrounding said primary, a condenser surrounding said magnetic shell and a casing surrounding said condenser.
5. A structure of the character set forth in claim 4, wherein the outer casing also is of magnetic material, said magnetic outer

casing and inner magnetic element serving 35 as part of parallel return magnetic circuits.

6. In a spark coil, a magnetic core, a secondary winding on said core and subject to the maximum magnetic field, a primary winding surrounding the secondary, a magnetic 40 element immediately surrounding the primary and providing a return magnetic circuit and a condenser outside said magnetic element and removed from the influence of the secondary.

7. In a spark coil, the combination of a secondary winding, a primary winding surrounding said secondary winding, a magnetic element immediately surrounding said primary winding and a condenser outside 50 said magnetic element.

8. In a spark coil, the combination of a secondary winding, a primary winding surrounding said secondary winding, a magnetic element immediately surrounding said 55 primary winding, a condenser surrounding said magnetic element and a casing inclosing said condenser and the parts within the same.

9. In a spark coil, a secondary winding, 60 a primary winding surrounding said secondary winding, a magnetic element immediately inclosing said primary winding, a condenser outside said magnetic element, a casing inclosing said condenser and end caps 65 engaged with said casing and closing the end portions of the coil structure.

JOHN F. CAVANAGH.
